CLAIM

The ornamental design for a bottle for cosmetics, as shown and described.

DESCRIPTION

FIG. 1 is a perspective view of a bottle for cosmetics of our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a sectional view thereof taken along line 8-8 in FIG. 2.

The dashed broken lines showing of the bottle for cosmetics are for the purpose of illustrating portions of the article, and the dot-dash broken lines define the bounds of the claimed design. The dashed broken lines and the dot-dash broken lines form no part of the claimed design.
